EJECTING MECHANISM FOR SLUG
CASTING MACHINESRansom H. Turner, Great Neck, N. Y., assignor to
Mergenthaler Linotype Company, a corporation
of New York

Application March 20, 1947, Serial No. 735,988

3 Claims. (Cl. 199—60)

1

This application is a division of application Serial No. 608,406, filed August 2, 1945, for a Slug Machine Using a Hand Stick.

The present invention is directed specifically to the slug ejecting mechanism embodied in that machine. This ejecting mechanism comprises, as usual, an ejector slide and an ejector blade, but differs from the usual construction in that the ejector slide is operable by an individual power unit, in the form of a pneumatic piston and cylinder arrangement, through the medium of a pair of toggle devices which carry the ejector blade and are adapted, prior to the active stroke of the slide, to advance the blade relatively thereto so as to increase the initial pressure exerted upon the base of the slug in breaking its adherence to the side walls of the mold cavity. As another departure, the ejecting mechanism includes safety means for stopping the operation of the machine in the event the ejector slide fails to complete its return stroke, as might occur, for instance, upon failure of operation of the individual power unit.

Referring to the drawings:

Fig. 1 is a front elevation of the ejecting mechanism, showing by the full lines the parts in their normal position and by the dotted lines the toggle connections between the ejector slide and ejector blade straightened out to advance the blade relatively to the slide;

Fig. 2 is a front elevation similar to Fig. 1 but showing the relative position of the parts during the ejection of the slug from the mold; and

Fig. 3 is a horizontal section taken on the line 3—3 of Fig. 1.

The reciprocable ejector slide G is arranged between the two front flanges D⁵, D⁶ of the bracket D and is formed with a pair of vertically disposed side members G¹, which latter are connected together by an integral offset web portion G² and provided with tongues g extending longitudinally thereof and engaging in corresponding grooves or guideways d¹² formed in said flanges. The ejector slide G is equipped, as usual, with an ejector blade G³ but, according to the present invention, the blade instead of being attached directly to the slide is carried by a horizontal subsidiary slide bar G⁴, the latter (Fig. 3) being arranged between the vertical side members G¹ of the ejector slide and connected thereto by tongues and grooves g¹ in order to be capable of a limited vertical movement in relation to the slide.

In the preferred embodiment illustrated, the slide bar G⁴ is operated by a pair of pneumatically controlled toggle devices G⁵, each comprising a lever g² and a link g³, the former being pivoted to the upper end of the contiguous side member G¹ of the ejector slide, and the latter connecting the shorter arm of said lever to one end of the bar G⁴. An adjustable banking screw g⁶, arranged to engage the upper edge of the web portion G², limits the upward movement of the ejector slide, and a lug g⁷ projecting forwardly from the web and overlying the bar G⁴, limits the upward movement of the bar and thus locates the ejector blade in its normal or slug ejecting position (Fig. 1). The longer horizontal arms of the toggle levers g² are appropriately connected with the stem of a piston G⁸ which is mounted in an upright air cylinder G⁷ secured to the main bracket D and arranged directly above the ejector slide G.

Operation of the piston G⁸ is controlled by air lines g⁹, g¹⁰ leading from a manifold (not shown) to the opposite ends of the cylinder G⁷. Normally, air pressure in the bottom of the cylinder sustains the ejector slide through the medium of the bar G⁴ and toggle devices G⁵ (now partially collapsed) in its raised position shown in Fig. 1, with said bar engaging the lug g⁷ and with the web portion of the slide engaging the banking screw g⁶. However, as soon as the air pressure is reversed to the top of the cylinder through the pipe line g⁷, the toggle devices G⁵ will be straightened out and force the ejector blade G³ downwardly far enough to overcome the initial resistance presented to the blade at the start of the slug ejecting operation. As the toggles are straightened out, the shorter arms of the levers g² are adapted to bank against the contiguous side members of the ejector slide G and thereby establish a positive connection between the slide and the piston G⁸, so that the latter by its continued downward movement may impart a full active stroke to the ejector blade for the complete ejection of the slug from the mold B. As a slug is ejected, it passes through an elongated clearance aperture d¹³, formed in the rigid cross bar D⁸, and is received by an underlying conveniently located trough or galley D⁹ fastened to the rear wall of the aperture. Air now is exhausted from the top of the cylinder G⁷ through the pipe line g⁷ and re-admitted under pressure at the bottom through the pipe line g⁸. In rising, the piston G⁸ will first collapse the toggle sufficiently to raise the subsidiary slide bar G⁴ into engagement with the projecting lug g⁷ of the web G² and then, as it continues its upward movement, restore the ejector slide to its original position against the banking screw g⁶.

2

The use of toggle devices for imparting the initial stroke to the ejector blade is particularly advantageous when, as herein, the blade is operated pneumatically. As well understood in the art, the greatest pressure which the ejector blade must exert is at the start of the slug ejecting operation when it is called upon to break the adhesion of the slug with the mold; thereafter, the resistance offered by the slug is much less and little more than is required for the slug trimming operation. It is evident, therefore, that a much smaller pneumatic piston may be used with the toggle devices than without them.

The mold B is provided at its opposite ends with tongues b arranged to fit in fore-and-aft grooves d¹¹ formed in the front flanges D⁵ and D⁶ of the main bracket D, whereby the mold is accurately guided as it is moved horizontally to and from the ejecting station. Safety means are employed to stop the operation of the machine if the mold should not move forward to the ejecting position at the proper time. Such means comprise a short horizontal rock shaft 13 having two depending arms 14 and 15, the former being equipped with an adjusting screw 16 disposed in the path of the mold, and the latter being operatively connected to the stop devices through a Bowden wire 9. Danger of breakage or serious damage to the ejecting mechanism, the operation of which immediately follows the arrival of the mold at the ejecting station is thus averted.

A safety attachment is also provided for stopping the operation of the machine in the event the ejector slide G is not raised high enough, after the slug ejecting operation, for the attached blade G³ to clear the mold B as the latter is withdrawn from the ejecting station. Said safety attachment includes a small bell-crank lever 41 pivoted to the front guiding flange D⁶ of the U-shaped bracket D and having one of its arms connected through a Bowden wire 42 to the stop devices. The other arm of the lever 41 is equipped with an adjusting screw 43 located above and in the vertical path of the contiguous upright side member G¹ of the ejector slide G, so that the lever will be rocked in the proper direction to disable the stop devices as the slide G completes its upward movement (see Fig. 1). If, however, anything should interfere with the normal operation of the ejector slide, the lever 41 will remain in the position shown in Fig. 2 and cause

disengagement of main clutch before the mold B starts its retreat from the ejecting station.

In the accompanying drawings, the improvements have been shown merely in preferred form and by way of example, and it should therefore be understood that the invention is not limited to any specific form or embodiment except insofar as such limitations are specified in the appended claims.

Having thus described my invention, what I claim is:

1. In a slug casting machine equipped with a mold and slug ejecting mechanism, said mechanism including, in combination, a reciprocable ejector slide, an ejector blade mounted for movement relatively to the ejector slide in the direction of the slug ejection, and intermediate power-multiplying connections whereby the blade, prior to the active stroke of the slide, is advanced relatively thereto sufficiently far to break the adherence of the slug to the side walls of the mold cavity.

2. A combination according to claim 1 wherein the slug ejecting mechanism also includes pneumatically controlled means for operating the ejector slide.

3. A combination according to claim 1 wherein the slug ejecting mechanism also includes pneumatically controlled means for operating the ejector slide, and wherein the power-multiplying connections between said slide and ejector blade includes a pair of toggle devices operable by said means and through which the advance movement of the ejector blade is effected under increased pressure.

RANSOM H. TURNER.
